TOY BEAUTY SALON

Osamu Takahashi, Tokyo, Japan, assignor to Tomy Kogyo
Co., Inc., Tokyo, Japan

Filed Aug. 27, 1974, Ser. No. 500,935

Term of patent 14 years

Int. Cl. D21—01

U.S. Cl. D34—15 AC

FIG.1

FIG. 1 is a left front perspective view of a toy beauty salon showing my new design;

FIG. 2 is a front elevational view thereof with the chair and dryer positioned to the left side, the rear, not shown, being substantially plain and unornamented;

FIG. 3 is a top plan view of FIG. 2; and

FIG. 4 is a right side elevational view of FIG. 2.

I claim:

The ornamental design for a toy beauty salon, as shown and described.
